UNITED STATES PATENT OFFICE.

KENNETH M. BROGDON AND CHRISTOPHER L. HOWSER, OF SMACKOVER, ARKANSAS.

DEEP-WELL EMERGENCY VALVE.

Application filed March 25, 1926. Serial No. 97,388.

Oil, gas, artesian and other deep wells frequently get beyond control particularly during the boring or sinking operations and, in the case of burning oil and gas wells, considerable damage results in addition to the loss experienced.

The present invention provides a valve which may be applied to the well casing during the sinking of the well, or which may be applied thereto in an emergency as occasion may require, to admit of the flow being checked or controlled and thereby obviate waste and damage.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a sectional view illustrative of an embodiment of the invention,

Figure 2 is a detail sectional view on the line 2—2 of Figure 1 looking in the direction of the arrows.

Figure 3 is a detail sectional view on the line 3—3, and

Figure 4 is a fragmentary view showing the pivoted end portions of the sections comprising the valve casing.

Corresponding and like parts are referred to in the following description and designated in the several views of the drawings by like reference characters.

The numeral 1 designates the well casing or pipe and mounted thereon is a valve embodying the invention.

The valve casing comprises similar complementary sections 2 which are pivotally connected, as indicated at 3. The sections 2 are outwardly flanged along their meeting edges and are connected by bolts 4 passing through registering openings formed in the outstanding flanges. The valve casing comprises a pipe receiving portion 5 and a valve receiving portion 6. These two portions 5 and 6 are disposed relatively at a right angle to each other. The opening formed in the portion 5 below the valve containing portion is

of a slightly less diameter than the pipe 1 to admit of the latter being firmly gripped between the sections when the latter are clamped after being fitted about the well casing. The opening in the pipe receiving portion 5 above the valve containing portion 6 is slightly larger than the pipe 1 to admit of ready removal of the upper portion of the pipe when severed or cut from the main part of the pipe 1. This opening is internally threaded, as indicated at 7 to receive the usual wedge nipple whereby to lubricate the well and bring it back to normal condition.

The valve containing portion 6 of the casing receives a plug valve 8, a reamer 9, a drill point 10, a stem 11 and a nut 12. The valve 8, reamer 9 and drill point 10 are fixed upon the stem 11 and move therewith. The nut 12 is fixed in or to the casing and cooperates with the threaded portion of the stem 11 to positively advance the latter when the stem is rotated. A hand wheel 13 fixed to the outer end of the stem 11 provides convenient means for rotating said stem to advance the drill, reamer and valve. A packing 14 located in a recess in the outer end of the part 6 maintains a close joint between the stem 11 and the casing. This packing is held in place by means of a gland 15 bolted or otherwise secured to the outer end of the part 6. The opening formed in the part 6 of the valve casing is contracted at the end adjacent the pivot 3, as indicated at 16 so as to accommodate the reamer 9 and the drill-point 10. To maintain the sections 2 in alignment a rib or flange 18 is formed upon the inner or meeting face of one of the sections adjacent the opening therein and is adapted to enter a corresponding recess formed in the abutting face of the companion section. This is shown most clearly in Figures 3 and 4 of the drawings. This also insures a close fit between the meeting faces of the sections.

To further secure the valve casing to the pipe 1 an anchoring device is clamped thereon and comprises companion sections 19 which are clamped about the pipe 1 by means of bolts 20 which pass through openings formed in outstanding ears of the sections. A lug 21 projecting outwardly from each of the sections 19 receives the eye of a stem 22. A hook 23 projecting outwardly from each of the sections 2 receive the eye of a stem 24. The two stems 22 and 24 are

connected by means of a nut 25. In this manner the connection between the anchoring device and the valve casing may be tightened or adjusted by turning the nut 25 5 in a manner readily understood.

When boring a well, the emergency valve may be secured to a length of pipe or pump casing 1, as a precautionary measure for immediate use in an emergency. However, 10 the construction is such as to admit of the emergency valve being secured to the projecting portion of the well pipe or casing when an emergency arises requiring the out-flow to be checked or cut off. When the 15 valve is in position upon the pipe 1 the drill point 10, reamer 16, and valve plug 8 are located to one side of the pipe 1 and when it is required to control the well the stem 11 is rotated in a direction to advance the cutting tool and valve. The drill 10 is of a 20 length to penetrate a side of the pipe 1 and to form an opening therein to receive the advancing end of the conical reamer or cutter 9. The base of the conical reamer or 25 cutter 9 is of a diameter corresponding to the diameter of the valve plug 8 and to the external diameter of the pipe 1, so as to cut through the latter. When the cutter is fully advanced it occupies the contracted 30 portion 16 of the opening formed in the part 6 of the valve casing. At the same time the valve plug 8 extends across the pipe 1 and closes the same, thereby cutting off the flow from the well. The upper portion of 35 the pipe 1 separated by the cutter is removed and the usual wedge nipple, not shown, is fitted to the threaded portion 7 of the pipe receiving portion 5 of the valve casing to admit of the well being lubricated 40 and brought back into normal condition in a manner well understood.

Having thus described the invention, we claim:

1. An emergency valve for well casing, 45 comprising a casing having intersecting openings, the one adaptable to receive the well casing, and a cutter and valve plug in the other opening and means for simultaneously advancing the cutter and valve to 50 sever the well casing and at the same time close the valve.

2. An emergency valve for cutting off the flow of a well, the same comprising a casing having intersecting openings, the one 55 to receive the well casing, and a cutter and a valve in the other opening, said cutter comprising a drill point and a conical reamer, and a stem mounted in the valve casing and carrying the said cutter 60 and valve.

3. An emergency valve of the character 65 specified, comprising a casing having intersecting openings, a cutter and a valve disposed in one of the openings and adapted to operate across the other opening, and a

stem carrying the cutter and the valve and threaded into the casing to effect positive feed of the cutter and valve simultaneously with the rotation thereof.

4. An emergency valve of the character 70 specified, comprising a valve casing formed with a valve receiving opening and an intersecting well casing receiving opening, the upper portion of the latter opening being enlarged and internally threaded, a cutter and 75 a valve in the first-mentioned opening, and a stem carrying the cutter and valve and threaded into the valve casing.

5. An emergency valve of the character 80 specified, comprising a valve casing in which is formed intersecting openings, the one adapted to receive the well casing and the other having an end portion contracted, a cutter and a valve in the last-mentioned opening, said cutter comprising a drill point 85 and a conical reamer, and a stem carrying said cutter and valve and threaded into the valve casing.

6. An emergency valve of the character 90 specified, comprising a valve casing formed with intersecting openings, a cutter and a valve in one of said openings, a nut fixed 95 in the opening of the casing containing the cutter and valve, and a stem carrying the cutter and valve and threaded into the said nut.

7. An emergency valve comprising a valve casing, comprising similar sections, said casing having intersecting openings formed partly in each of the sections, means for 100 clamping the sections about a well casing, a cutter and a valve in one of the openings of the valve casing and a stem carrying the cutter and valve and threaded into the valve casing.

8. An emergency valve comprising a valve casing formed of similar sections which are pivoted at one end, said casing having intersecting openings formed partly in each of the sections, a cutter and a valve in one of the 110 openings of the casing and a stem carrying the cutter and valve and threaded into the valve casing.

9. An emergency valve of the character 115 specified, comprising a casing formed with intersecting openings, and comprising similar sections pivoted at one end, means for drawing the sections together and securing them in operative position, a cutter and a 120 valve in one of the said openings, said cutter comprising a drill point and conical reamer, a nut fixed in the opening of the casing containing the cutter and valve, and a stem carrying the cutter and valve and threaded into the said nut.

10. A casing head comprising a body formed in two pieces, means to clamp said pieces about the casing, a gate in said body and means to operate said gate to close the 130 passage through the head, a sharp cutting

edge on said gate whereby said gate is adapted to cut through the casing to stop the flow therethrough.

11. A casing head comprising a body formed in two pieces, flanges on said pieces, bolts extending through said flanges whereby the pieces are clamped around the casing, a gate in said body and means to operate

said gate to close the passage through the head, a sharp cutting edge on said gate 10 whereby said gate is adapted to cut through the casing to stop the flow therethrough.

In testimony whereof we affix our signatures.

KENNETH M. BROGDON.

CHRISTOPHER L. HOWSER.
